UNITED STATES PATENT OFFICE.

WILLIAM H. BANZETT, OF BERGENFIELD, NEW JERSEY, ASSIGNOR TO MERCANTILE CORPORATION, OF NEW YORK, N. Y., A CORPORATION OF NEW YORK.

MACHINE FOR MAKING WINDOW-ENVELOP BLANKS.

1,104,162.

Specification of Letters Patent.

Patented July 21, 1914.

Application filed November 26, 1912. Serial No. 733,596.

To all whom it may concern:

Be it known that I, WILLIAM H. BANZETT, a citizen of the United States, and a resident of Bergenfield, in the county of Bergen and 5 State of New Jersey, have invented certain new and useful Improvements in Machines for Making Window-Envelop Blanks, of which the following is a specification.

This invention relates to machines for 10 making envelopes and particularly to means for performing certain steps in the manufacture of those envelopes having a transparent window in the face thereof.

The object of my improvements is to provide 15 means for rapidly and accurately furnishing envelop blanks embodying those features particularly characteristic of envelopes of the character specified.

With these ends in view I preferably employ 20 mechanism illustrated in the drawings accompanying this specification wherein—

Figure 1 is a diagrammatic sectional elevation of my improved machine. Fig. 2 is a plan view of a window envelop blank as 25 produced in said machine. Fig. 3 is a diagrammatic elevation illustrating the arrangement of gearing and some of the cam mechanism. Fig. 4 is an elevation, to an enlarged scale, of a detail of my machine.

30 Mounted on supports as 2, and resting against rail 3 is a pile of ordinary envelop blanks 4. In front of and near the lower edge of said pile, transfer cylinder 5 is fixed to shaft 6. Above said cylinder 5, take-off 35 finger 7 is oscillatably mounted at 8. Said finger 7 may be provided at its lower end with some suitable, well known means for engaging the front blank of the pile and, as finger 7 is oscillated to the right, Fig. 1, 40 for delivering that blank to the grip of clips, as 10, on cylinder 5. I have illustrated suction means for engaging said front blank. Finger 7 is of tubular construction and is provided near its lower end with 45 ports 9. Air may be exhausted at suitable times through hollow shaft 8 by some suitable exhaust means. For oscillating finger 7 I provide arm 41 fixed to shaft 8 and having at its lower end roll 42 for engagement 50 with cam 43 fixed to shaft 6. Clips, as 10, are fixed to shaft 44, as is arm 45, having roll 146 for engagement with fixed cam 147. Said cam 147 may be held in fixed position 55 relatively to cylinder 5 by some convenient well known means not shown.

To the right of cylinder 5 and coacting therewith is rotary blank-bed or platen cylinder 11 on shaft 12. Said cylinder is provided with clips as 13, for gripping the blank. Said cylinder may also be provided 60 with one member 14 of a pair of cutting dies. The other member 16, of said pair of cutting dies may be mounted for reciprocation toward and from said die 14, on the lower end of slide 17 above cylinder 11. 65 Said slide 17 may be conveniently mounted in guides 18, fixed to the frame of the machine not shown. Said dies 14, 16 are efficient for cutting the window openings as 20 in the blanks as 40, Fig. 2. Said clips, as 70 13, are fixed to shaft 46, as is arm 47 having roll 48 for engagement with fixed cam 49.

For removing the severed window blank from the envelop blank I provide die 16 with spear 50 which, as dies 14, 16 coact, 75 pierces the window blank portion of the envelop blank in coaction with the window blank supporting edges of pocket 83 in die 14 of rotary head 11, and when that window blank portion is severed from the envelop 80 blank, conveys it upwardly as die 16 recedes, where it may be removed from said spear by means of stripper 51 mounted for reciprocation lengthwise slide 17. Said stripper is provided with pin 52 for coaction with fixed arm 53 of one of guides 18. Above cylinder 11 rotary gummer 19 is fixed to shaft 21 and adjacent to the upper portion 85 of the path of travel of said gummer is gum delivery mechanism 22. 90

To the right of cylinder 11 is the mechanism for delivering consecutively to the gummed faces of the blanks respectively, patches of transparent paper. This mechanism comprises shaft 23 for holding a roll, 95 as 36, of transparent paper in a continuous strip, upper and lower feed rolls 24, 25, fixed cutter 26, below the path of said strip, and oscillating cutter 27, above the path of said strip, for coaction with lower cutter 26. 100 Rotary patch-bed or delivery cylinder 28 fixed to shaft 39, is provided with grippers as 29, and which grippers may be mounted for retraction below the periphery of said cylinder 28. Said grippers, as 29, are fixed 105 to shaft 54 in the free end of arm 55 and which arm is fixed to shaft 30 in cylinder 28. Also fixed to shaft 54 is arm 56 having roll 57 for engagement with fixed cam 58. Springs 59 and 60 are arranged for urging 110

clips, as 29, to their inoperative positions, spring 59 being weaker than spring 60, whereby said clips, as roll 57 passes around cam 58, will be first moved outwardly and then downwardly into coaction with the periphery of cylinder 28 for gripping the leading end of a patch portion 33.

For feeding web 32, rolls 24, 25, are geared together by gears 61, 62, and coaxially fixed with roll 25 is ratchet 63. Said ratchet may be rotated intermittently from cam 64 by the usual mechanism therefor, particularly illustrated in Fig. 1. For oscillating upper knife 27 I employ cam 65, fixed to shaft 39 for rotation with cylinder 28. Said knife is fixed to the outer end of arm 66, freely pivoted on shaft 67 of roll 24, and said arm 66 is operatively connected with cam 65 by the usual means. Below cylinders 11 and 28 are coacting delivery rolls 37, 38 respectively.

To enable die 16 to coact with die 14 it is necessary that the rotary movement of cylinder 11 be intermittent and that said cylinder have a period of rest in the position shown in Fig. 1. I therefore provide intermittent driving means comprising in its preferred embodiment the well known rotating arm 70 having roll 71 for successive engagement with slots as 73 in disk 72. Arm 70 is fixed to shaft 74 and which shaft may be considered the main shaft of the machine and may be rotated at uniform constant speed from some source of power not shown. Slotted disk 72 is fixed to shaft 75 as is gear 76 driving gear 77 fixed to shaft 6. Disk 72 is illustrated as having four slots 73 and gear 76 is four times the diameter of gear 77, whereby for each revolution of shaft 74, shaft 75 rotates one quarter of a revolution and shaft 6 rotates one complete revolution. Gear 78 also fixed to shaft 6 drives gear 79 fixed to shaft 12 and gear 79 drives gear 210 fixed to shaft 21. Gear 210 drives gear 80 of gummer 22. Gear 79 also drives gear 81 fixed to shaft 39 and gear 81 through intermediate gear 82 drives gear 92 of discharge roll 38. Gear 92 drives gear 84 of the other discharge roll 37.

For actuating slide 17 I fix crank 85 to shaft 74 and by means of pitman 86 connect that crank with arm 87 fixed to rock shaft 88. Arm 89 is also fixed to said rock shaft 88 and has its bifurcated outer end in engagement with pin 90 fixed in slide 17.

The operation of my improved machine is as follows: A quantity of envelop blanks 4, of suitable profile having been placed upon the supporting rods as 2 and against bar 3, main shaft 74 is started in rotation at uniform speed in anti-clockwise direction. As illustrated in Fig. 1, finger 7 has previously been oscillated to its dotted position where it engages the lower end of the foremost blank and has then been swung to its

full-line position into a channel provided therefor in the periphery of cylinder 5 and has delivered the lowermost end of that blank into the grip of clips as 10 of cylinder 5, just at the end of that cylinder's last prior rotation. Therefore, now, immediately upon the commencement of the rotation of shaft 74 from the position shown in Fig. 3 cylinder 5 will commence its rotation in anti-clockwise direction and carry the envelop blank 75 downwardly and then upwardly to engagement with cylinder 11 whereupon grippers as 13 of that cylinder grip the leading end of the blank. Grippers 10 thereupon release their hold and the blank is carried around 80 upwardly on cylinder 11 until that cylinder presents its die 14 in the position shown in Fig. 1. At this time roll 71 of arm 70 will be just leaving that slot 73 indicated by position 73^a of Fig. 3. At this time crank 85 will be moving upwardly, thereby causing, through the connections described, slide 17 to move downwardly, presenting die 16 to engagement with die 14 whereby window opening as 20 will be cut in the blank. 90 Then as crank 85 moves downwardly about shaft 74 slide 17 will be withdrawn upwardly. During the coaction of dies 16 and 14 spear 50 will pierce the window blank portion of the envelop blank and as said die 95 16 is retracted upwardly will carry that window blank away from the envelop blank. Thereupon pin 52 will engage arm 53, whereby stripper 51 will push the window blank off from engagement with spear 50. Said 100 window blank will then fall from the machine or may be conveyed away by some convenient known means not shown. Arm 70 then continues its rotation and upon roll 71 engaging the next succeeding slot of disk 105 72, cylinder 11 will begin another rotation in clockwise direction, presenting the window margin of the blank to gummer 19 rotating in anti-clockwise direction in suitable time therewith. Said gummer thereupon deposits gum 31 around the border of the window opening 20.

During that rotation of cylinder 11 just previous to the one in which it coacts with the gummer, web 32 of transparent paper from roll 36 has been advanced by feed rolls 24, 25 by means of the mechanism provided therefor, over lower knife 26 in position to be gripped by clips as 29 of delivery cylinder 28. Clips 29 then grip the forward end of said web to cylinder 28 and shortly thereafter knife 27 descends and severs window patch portion 33. Said patch portion 33 is then ready for delivery against the gummed margin of the window in the envelop blank on cylinder 11 and as that blank passes downwardly to the right, said patch will pass downwardly to the left and be delivered against said gummed window margin. As said patched blank passes be- 130

tween cylinders 11 and 28 the patch is firmly squeezed onto the blank, the clips of the respective cylinders release their hold and the patched blank is delivered to the grip of 5 rolls 37, 38 by which it is discharged from the machine.

I claim:

1. A machine of the class specified including in combination, a rotary blank-bed, 10 means for intermittently rotating said blank-bed, rotary means for delivering blanks one at a time to said blank-bed, means on said blank-bed for gripping a blank, a cutter for coaction with said rotary bed between the intermittent rotations thereof for cutting a window opening in the blank on said bed, rotary means for delivering gum to the window margin of said blank, and rotary means for delivering a 15 patch against said gummed margin.

2. A machine of the class specified including in combination, a rotary blank-bed, means for intermittently rotating said blank-bed, rotary means for delivering blanks one at a time to said blank-bed, means on said blank-bed for gripping a blank, a reciprocating cutter for coaction with said rotary bed between the intermittent rotations thereof for cutting a window 20 opening in the blank on said bed, means for removing the window blank from the first mentioned blank, rotary means for delivering gum to the window margin of the first mentioned blank, and rotary means for delivering a patch against said gummed margin.

3. A machine of the class specified including in combination, a rotary blank-bed, means for intermittently rotating said blank-bed, means for delivering blanks one at a time to said blank-bed, means on said blank-bed for gripping a blank, a cutter for coaction with said rotary bed between the intermittent rotations thereof for cutting a window 25 opening in the blank on said bed, means carried by said rotary bed for delivering the window blank to said cutter, means carried by said cutter for successively retaining and discharging the window blank from said 30 cutter, means for delivering gum to the window margin of the first mentioned blank, and means for delivering a patch against said gummed margin.

4. A machine of the class specified including in combination, a rotary blank-bed, 35 means for intermittently rotating said

blank-bed, means for delivering blanks one at a time to said blank-bed, means on said blank-bed for gripping a blank, a cutter for coaction with said rotary bed between the intermittent rotations thereof for cutting a window opening in the blank on said bed, means carried by said rotary bed for delivering the window blank to said cutter, means carried by said cutter for successively retaining and discharging the window blank therefrom, a rotary gummer for delivering gum to the window margin of the first mentioned blank, means for delivering gum to the rotary gummer, a rotary patch-bed 40 for coaction with the rotary blank-bed, means for delivering patches one at a time to said rotary patch-bed, means on said patch-bed for gripping a patch, and means for rotating said blank-bed and said patch-bed in coaction for delivering said patch onto said gummed window margin of the blank.

5. A machine of the class specified including in combination, a rotary blank-bed, 45 means for intermittently rotating said blank-bed, means for delivering blanks one at a time to said blank-bed, means on said blank-bed for gripping said blank, a cutter for coaction with said rotary bed between the intermittent rotations thereof for cutting a window opening in the blank on said bed, a rotary gummer for delivering gum to the window margin of the blank, means for delivering gum to the rotary gummer, 50 a rotary patch-bed for coaction with the rotary blank-bed, means on said patch-bed for gripping a patch, means for advancing a continuous web of transparent paper, and for delivering the leading end of said web 55 in position to be engaged by the rotary patch-bed gripping means, means for severing a patch portion from the leading end of said web, means for rotating said blank-bed and said patch-bed in coaction for delivering said patch onto said gummed window margin of the blank, and means for actuating and timing the several instrumentalities with each other.

Signed at New York, in the county of 105 New York and State of New York, this 23 day of November 1912, before two subscribing witnesses.

WILLIAM H. BANZETT.
